UNITED STATES PATENT OFFICE.

LEWIS C. BAYLES, OF EASTON, PENNSYLVANIA, ASSIGNOR TO INGERSOLL-RAND COMPANY, OF NEW YORK, N. Y., A CORPORATION OF NEW JERSEY.

PERCUSSIVE TOOL.

1,089,038.

Specification of Letters Patent. Patented Mar. 3, 1914.

Application filed February 3, 1912. Serial No. 675,292.

To all whom it may concern:

Be it known that I, LEWIS C. BAYLES, a citizen of the United States, and resident of Easton, in the county of Northampton and State of Pennsylvania, have invented a new and useful Improvement in Percussive Tools, of which the following is a specification.

The object of this invention is to provide a novel form of automatic rotation device which will be very simple and compact, which rotation device is under the control of the valve which controls the operation of the tool.

In the accompanying drawings, Figure 1 represents in longitudinal central section a percussive tool with my improved rotation device applied thereto, Fig. 2 is a transverse section taken in the plane of the line A—A of Fig. 1, Fig. 3 is a transverse section taken in the plane of the line B—B of Fig. 1, and Fig. 4 is a diagrammatic view showing more clearly the construction of the controlling valve, its chamber and the passages leading therefrom to the work piston chamber and the rocking piston chamber.

The work piston is denoted by 1 and the chamber within which it reciprocates by 2. The tool cylinder is denoted by 3, its front head by 4, the front head washer by 5, the back head by 6, the rocking piston chest by 7, 8, and the handle, of usual form, by 9, which handle contains the usual oil supply chamber 9*.

The pressure fluid operated rocking piston is denoted by 10 and the chamber within which it oscillates by 11. The valve 12 which controls the operation of the work piston 1 and rocking piston 10 is situated in a valve chest 13.

The drill steel shank is denoted by 14 and its chuck by 15, which chuck is rotatably mounted in the front head 4 and has an enlarged bore 16 into which the rear end of the drill shank 14 extends in position to be struck by the extension 17 of the work piston 1.

The oscillating rocking piston 10 is fixed to the rear end of a rock shaft 18 which extends longitudinally from front to rear of the tool through the cylinder 3. The front end of this rock shaft 18 is extended into

the front head 4 and has a driving connection with the chuck 15 whereby the rocking movement of the shaft will impart a step by 55 step rotary movement in one direction to the chuck. This driving connection is shown herein as a pawl and ratchet clutch connection, the ratchet 19 being on the chuck 15 and the spring pressed pawl 20 being carried by a collar 21 fixed to the shaft 18.

The valve 12 herein shown is of the well known double winged type, one wing controlling the inlet passages 21, 22, leading to the ends of the work piston chamber 2 and 65 the inlet passages 25, 26, leading to the opposite sides of the rocking piston chamber 11, the other wing controlling the exhaust passages 23, 24, leading to the work piston chamber 2 intermediate the inlet passages 70 21, 22. It will thus be seen that the valve 12 controls the movements of the work piston 1 and the rocking piston 10.

It will be seen that the rotation device, as herein shown and described, is a very simple 75 and compact one.

While I have shown this rotation device as applied to a pressure fluid operated percussive tool of the piston hammer type, I do not wish to limit myself to such application 80 but contemplate its use in connection with percussive tools of any type.

What I claim is:—

1. In a percussive tool, a chuck and means for rotating it comprising a rock shaft, a 85 fluid pressure operated rocking piston carried thereby at the rear of the tool and a driving connection between the shaft and chuck.

2. In a percussive tool, a chuck, a rock 90 shaft, a fluid pressure operated rocking piston, carried thereby at the rear of the tool, and a clutch connection between the shaft and chuck.

3. In a percussive tool, a chuck and means 95 for rotating it comprising a rock shaft extending longitudinally from front to rear of the tool, a fluid pressure operated rocking piston fixed to the shaft at the rear of the tool and a driving connection between 100 the shaft and chuck at the front end of the tool.

4. In a percussive tool, a chuck and means for rotating it comprising a rock shaft ex-

tending longitudinally from front to rear of the tool, a fluid pressure operated rocking piston fixed to the shaft at the rear of the tool and a clutch connection between the shaft and chuck at the front of the tool.

In testimony, that I claim the foregoing as my invention, I have signed my name in

presence of two witnesses, this first day of February, 1912.

LEWIS C. BAYLES.
